UNITED STATES PATENT OFFICE.

LEWIS H. HANEY, OF LOS ANGELES, CALIFORNIA, ASSIGNOR TO STANDARD DEEP WELL PUMP CO., INC., OF LOS ANGELES, CALIFORNIA, A CORPORATION OF CALIFORNIA.

PUMP.

Application filed July 14, 1922. Serial No. 575,081.

To all whom it may concern:

Be it known that I, LEWIS H. HANEY, a citizen of the United States, residing at Los Angeles, in the county of Los Angeles and State of California, have invented new and useful Improvements in Pumps, of which the following is a specification.

This invention relates to pumps and more particularly to deep well, screw pumps.

10 It is one of the objects of the present invention to materially increase the efficiency of deep well screw pumps and to that end the invention involves the introduction into the pump pipe of one or more fixed guide vanes having the function of receiving the swirling water with such a reaction as to facilitate in the upward movement of the water and to decrease the stopping or checking reaction as occurs when the blades are not designed to secure a progressive reaction.

20 Another object of the invention is to provide a deep well pump having an efficient organization of rotating impellers, and to provide for the effective lubrication of the running parts. Also it is an object to obtain a simplified, practicable, substantial and durable organization.

25 Further objects and advantages will be made manifest in the following specification of an embodiment of the invention illustrated in the accompanying drawings, wherein:

30 Figure 1 is a longitudinal central section of the improved pump.

35 Figure 2 is a longitudinal central section showing the runners or impellers in elevation.

40 Figure 3 is an end perspective looking into one of the removable diffusion guide sleeves.

45 Figure 4 is a side elevation and partial longitudinal section of one of the diffusion sleeves.

50 The improved pump is of a type having any suitable number of column or pipe sections 2, having exterior right-hand threads 3 to receive threaded sockets 4 of a coupling tube 5. It is understood that the coupling threads 3 may be either right-hand or left-hand according to the direction of rotation of an impeller shaft 6 extending centrally through the column pipe 2 and through the couplings or shells 5, only one of which is shown. If the coupling threads 3 are right-

hand, then the direction of rotation of the 55 impeller shaft 6 will be left-hand as here shown.

An important object of the invention is to provide for the facile assembly and setting of the pumping means, and these means are 60 here shown as arranged within the coupling shell 5, the upper end of which is provided with an enlarged bore to receive a diffusion member including a sleeve 7 adapted to be slipped into the shell end and fastened in 65 any suitable manner as by key ball 8, which when removed, enables the withdrawal of the slipped sleeve 7. This sleeve is provided with a central hub 7' and from this there extends a plurality of tangential diffusion 70 vanes or blades 7", the peculiar construction of which will be described more hereinafter.

About at its longitudinal center the coupling shell is shown as slightly enlarged at 75 5' and has a plurality of inwardly extending tangential blades 5", carrying a central bearing 10'. In this bearing there is suitably fixed an elongated bushing 11 which projects beyond the ends of the bearing 10 and is locked as by a key ball 12. This 80 bushing has adjacent to its ends exterior grease receiving grooves 13 and the bore of the bushing 11 is provided with a lubricant chamber 11', upwardly from which extends a helical groove 11", whereby lubricant is conducted upwardly into the bore of a runner hub 15. This hub has helical, impelling blades 16 of suitable length and pitch, and in the upper end of the impeller there is threaded the tubular driving shaft 6, which 85 passes through the sleeve 7'. The lower end of the impeller hub 15 is provided with a skirt 15' which is of such diameter to receive the bushing 11 about which it rotates. The grease receiving grooves 13 in conjunction 90 with the skirt 15' provide, when the grooves are filled with grease, a satisfactory means for preventing entrance of sand or sediment to the interior of the grease chamber.

95 The bushing forms a bearing for an inner and intermediate short shaft 17, threaded in the hub 15 to be driven thereby, and this short shaft extends downwardly and is threaded at 17' in the hub 18 of a lower impeller 19, which includes a helical blade 100 or blades similar to the blades 16, both of which rotate in the contiguous portions, with a close running fit, of the shell 5. The 105

short shaft 17 is tubular. If the impeller 19 is the lowermost in a series of coupling shells 5, then the impeller hub 18 is closed by a plug 20, otherwise a tubular shaft section is introduced and extended to the next lower pump shell 5.

From the above it will be seen that the drive shaft 6 rotates the impeller 16 and this drives the short shaft 17, which in turn drives the lower impeller 19, while the bushing 11 forms a bearing for the short shaft and is held in the bearing 10.

One of the important objects of the invention is to provide for the efficient lubrication of deep well twin screw pumps, and in the present case lubrication is secured as by means of a central lubricant tube 22 which extends down through the hollow-shaped members and discharges just above the plug 20. Lubricant, and preferably a grease, is forced with sufficient pressure into the tube 22 to flow down through the same and thence upwardly thereby in the hollow shaft sections. The short shaft 17 is provided with a radial lubricant port 17^a through which the grease passes under pressure out into the grease chamber 11' in the bushing 11. From this the grease is carried upwardly by the groove 11^a.

30 In twin screw pumps the liquid receives a rotary motion as well as a longitudinal movement in the pump pipe and it is an object of the invention to utilize the energy of the liquid expended in rotation to accelerate the upward flow of the liquid. To that end the webs or vanes 5^a and 7^a are so designed as to react upon the rotating column of water and tend to lift the same. This is accomplished by curving the lower 40 ends of the blades 5^a and 7^a slightly forwardly as at *a*, Figs. 2 and 3, so that the leading edges of the blades will cut the revolving steam or water and the intercepted part thereof will be diverted upwardly. It 45 will be apparent that, if the diverting blades 5^a and 7^a are simply straight and parallel to the axis of the pump, the blades tend to retard the circular flow and also decrease the efficiency of the pump. By thus curving the blades as at *a*, the kinetic energy of 50 the water is utilized to accelerate upward flow.

Further embodiments, modifications and changes may be resorted to within the spirit 55 of the invention as here claimed.

What is claimed is:

1. In a deep well pump, a coupling shell having a central fixed tubular bearing support, an elongated bushing fixed in said 60 support, a short shaft rotatably mounted in the bushing, an impelling member having a hub fixed upon each end of the short shaft, said impelling members each having a skirt thereon, said skirts surrounding end portions of the bushing, the external di-

ameter of said skirts being substantially the same as the external diameter of the said hub.

2. In a deep well pump, a coupling shell having a central tubular supporting member, deflecting blades integrally uniting said tubular member and said shell, an elongated bushing secured in said member, a short shaft rotatably mounted within the bushing, an impelling member having a central hub secured upon each end of the short shaft, said hub at one end extending beyond the end of the said shaft to receive a drive shaft, said hub being rabbeted at the other end to receive said bushing. 70

3. In a deep well pump, a coupling shell having a central tubular supporting member, deflecting blades integrally uniting said tubular member and said shell, an elongated bushing fixed in said member, a short shaft rotatably mounted within the bushing, an impelling member having a hollow central hub fixed upon each end of the short shaft, said hub extending beyond the end of the short shaft to receive a drive shaft, said 80 impelling members each having a skirt spaced from the shaft and extending some distance along the bushing, lubricant holding grooves in the outer surface of the bushing adjacent the skirt and means to supply 85 lubricant to said grooves. 90

4. A coupling shell comprising a tubular member having means on each end thereof for securing it to a section of pipe, a plurality of inwardly extending tangential deflecting blades integral with said shell, said blades terminating at their inner ends in a hub providing a support, said hub having a bushing secured therein, a shaft rotatable in the bushing and extending beyond each end thereof, a water impeller secured on each end of the shaft, said impellers each including a hub portion extending beyond the end of said shaft, a drive shaft secured to each hub, each of said impellers having a skirt at one end thereof spaced from the shaft to provide an annular cavity, said bushing being arranged in said cavity, lubricating grooves in said bushing adjacent the skirt and means to supply lubricant to said 105 grooves. 110

5. A deep well pump composed of a plurality of coupling shells united by pipe casing, each coupling shell comprising a separate, detachable, and interchangeable unit consisting of a shell member having integral deflecting blades located therein, said blades surrounding a hollow hub member, a bushing within the hub member, a shaft journaled within the bushing, water 120 impellers mounted on each end of the shaft, said impellers having hubs secured to said shaft, said hubs extending beyond the ends of said shafts, drive shafts threaded in said extending threaded portion, skirts on 125

said impellers facing toward each other and spaced from the drive shaft, said bushing being located between the skirt and the drive shaft and means for making a tight joint 5 between the skirt and the drive shaft.

6. In a deep well pump, a unitary coupling shell having a central tubular supporting hub member arranged within and intermediate the ends thereof, deflecting 10 blades uniting said hub member and said shell, a shaft rotatably mounted within the hub, an impelling member having a hub fixed upon said shaft on each side of said central supporting member, a second supporting hub member having deflecting 15 blades and arranged adjacent one of said impellers and between said impeller and the end of the shell.

7. A deep well pump, composed of a plurality of coupling shells united by pipe sections, each of said coupling shells comprising interchangeable units, each composed of a shell member having deflecting blades 20 thereon, a hub member carried by said blades, a shaft journaled within the hub, 25

water impellers on opposite sides of said deflecting blades and mounted on said shaft, a second deflecting member arranged adjacent one of said impellers, and means whereby the last mentioned deflector is secured in 30 place by the connecting pipe.

8. A deep well pump, composed of a plurality of coupling shells united by pipe sections, each of said coupling shells comprising interchangeable units, each unit including 35 a casing having deflecting blades fixed therein, a hub carried by said blades, a shaft journaled within the hub, water impellers on opposite sides of said blades and mounted on said shaft, a rabbet at one end of the 40 coupling shell, a second deflecting member including a removable sleeve arranged in said rabbet, said sleeve having deflecting blades thereon, said rabbet being threaded to receive a pipe, whereby the sleeve is re- 45 movably secured in position.

In testimony whereof I have signed my name to this specification.

LEWIS H. HANEY.
